No. 682,056.

Patented Sept. 3, 1901.

J. S. GARZOUSI.

CONTACT FOR UNDERGROUND TROLLEYS.

(Application filed July 10, 1901.)

(No Model.)

UNITED STATES PATENT OFFICE.

JOSEPH SHOHAB GARZOUSI, OF NEW YORK, N. Y.

CONTACT FOR UNDERGROUND TROLLEYS.

SPECIFICATION forming part of Letters Patent No. 682,056, dated September 3, 1901.

Application filed July 10, 1901. Serial No. 67,703. (No model.)

To all whom it may concern.

Be it known that I, JOSEPH SHOHAB GARZOUSI, a subject of the Sultan of Turkey, and a resident of the city of New York, borough 5 of Manhattan, in the county and State of New York, have invented a new and Improved Contact for Underground Trolleys, of which the following is a full, clear, and exact description.

10 The object of the invention is to provide a new and improved contact for underground trolleys arranged to insure proper contact at all times, so as to prevent breaking of the current to the motor and the lamps of the car 15 when passing joints, switches, and the like.

The invention consists of novel features and parts and combinations of the same, as will be fully described hereinafter and then pointed out in the claims.

20 A practical embodiment of the invention is represented in the accompanying drawings, forming a part of this specification, in which similar characters of reference indicate corresponding parts in all the views.

25 Figure 1 is a plan view of the improvement as applied on a plow, the latter being shown in section. Fig. 2 is a similar view of the same with the parts in a different position. Fig. 3 is an enlarged transverse section of the 30 same on the line 3 3 in Fig. 1, and Fig. 4 is a sectional plan view of the same on the line 4 4 in Fig. 3.

A plow or slot-bar A of any approved construction extends through a slot B into a duct 35 C and carries at its lower end A', of insulating material, on opposite sides, sets of grooved rollers D, in which are mounted to slide longitudinally the side bars E of a contact-frame, the ends E' of which are made of insulating 40 material and arranged to connect the side bars E with each other. On the ends E' are held contact-points F, pressed into engagement with feed-wires G by the action of springs H, it being understood that two contact-points F on one side of the frame engage one of the feed-wires and the other two contact-points on the other side of the frame engage the return feed-wire. Suitable electric 45 connection is made between the rollers D and

the motor and the lamps of the car, so that 50 the electric current passes to the motor and the lamps and is returned to the return feed-wire. By having the frame arranged to slide loosely and freely on the sides of the plow A it is evident that when the car goes in the 55 direction of the arrow a' (see Fig. 1) then a portion of the frame extends rearwardly of the plow, so as to have the rear contact-points make contact with the feed-wires at the time the front contact-points pass over a joint to 60 insure an uninterrupted circuit at the time the forward points pass over the joint. When the car passes in the opposite direction, as indicated by the arrow b in Fig. 2, then the plow on the first forward motion slides along on the 65 frame until the forward end of the plow strikes the corresponding end E' and then carries the frame along, a portion of the frame extending rearward of the plow, as previously explained and for the purpose mentioned. 70

It will be seen that by the arrangement described a positive contact is always made to insure an uninterrupted circuit, especially as two contact-points are in contact with the main as well as with the return feed-wire. 75 The bars E are sufficiently flexible to permit of conveniently bending when the plow goes around curves without danger of disconnecting the contact-points F from the wires G.

Having thus fully described my invention, 80 I claim as new and desire to secure by Letters Patent—

1. A contact for underground trolleys, comprising a contact freely slidable on a plow and having contact-points at its ends to connect 85 with the main and the return feed-wires at the different points of their length, as set forth.

2. A contact for underground trolleys, comprising a contact-frame having contacts on 90 its ends and freely slidable on a plow, as set forth.

3. A contact for underground trolleys, comprising a contact-frame having contact-points at the ends, the frame being freely slidable 95 on its plow, and means for limiting the sliding of the frame on the plow, as set forth.

4. A contact for underground trolleys, com-

prising a frame having longitudinal bars with insulated ends, roller-bearings on the plow and in which are mounted to slide said bars, and contact-points on said ends of the frame 5 and in contact with the main and the return feed-wires, as set forth.

In testimony whereof I have signed my

name to this specification in the presence of two subscribing witnesses.

JOSEPH SHOHAB GARZOUSI.
